UNITED STATES PATENT OFFICE.

JAMES M. DAY, OF OMAHA, TEXAS.

POST-HOLE DIGGER.

1,121,615.

Specification of Letters Patent. Patented Dec. 22, 1914.

Application filed November 25, 1913. Serial No. 803,006.

To all whom it may concern:

Be it known that I, JAMES M. DAY, a citizen of the United States, residing at Omaha, in the county of Morris, State of Texas, 5 have invented certain new and useful Improvements in Post-Hole Diggers; and I do hereby declare the following to be a full, clear, and exact description of the invention, such as will enable others skilled in 10 the art to which it appertains to make and use the same.

This invention relates to post hole diggers.

The object of the invention resides in the 15 provision of a post hole digger which may be conveniently and efficiently operated and which embodies an improved means for removing the earth when same has become packed between the spade elements of the 20 digger.

A further object of the invention resides in the provision of a post hole digger which is simple in construction and which may be manufactured and sold at a comparatively 25 small cost.

With the above and other objects in view the invention consists in the details of construction and in the arrangement and combination of parts to be hereinafter more 30 fully described and particularly pointed out in the appended claim.

In describing the invention in detail reference will be had to the accompanying drawings wherein like characters of reference 35 denote corresponding parts in the several views, and in which—

Figure 1 is a view in elevation of a post hole digger constructed in accordance with the invention; Fig. 2, a vertical longitudinal 40 section of the digger; Fig. 3, a bottom view of the digger, and Fig. 4, a detail perspective view of one of the stripping elements of the digger.

Referring to the drawings the improved 45 digger is shown as comprising a handle 10 which has secured thereto at one end oppositely disposed spade elements 11 and 12, said elements being arcuate in cross section and disposed in opposition to each other. The 50 upper ends of the spade elements 11 and 12

are directed inwardly toward the handle 10 and provided respectively with openings 13 and these openings alined respectively with eye members 14 and 15 mounted on the handle 10. Slidably mounted in the eye members 14 and 15 and the openings 13 are rods 16 and 17 respectively. The upper ends of these rods terminate respectively in laterally directed portions 18 while the lower ends thereof have secured thereto respectively arcuate plates 19 bearing against the inner faces of the spade elements 11 and 12 and conforming to the contour of said faces. Mounted in each rod 16 and 17 and disposed between the eye members through 65 which said rods slide is a cross pin 20. Encircling the rod 16 between the eye members 14 is a spring 21 the lower end of which bears against the lower eye member 14 and the upper end thereof against the cross pin 70 20. Likewise the rod 17 is encircled by a spring 22 one end of which bears against the lower eye member 15 while the upper end thereof bears against the cross pin 20. These springs 21 and 22 serve to normally 75 hold the plates 19 at the top of the spade elements 11 and 12.

In the operation of the digger the spade elements are driven into the ground through the medium of blows against the upper end 80 of the handle. After the digger is removed from the ground the earth retained between the spade elements can be conveniently discharged by placing either the foot or the hand against respective portions 18 and then 85 moving respective rods 16 and 17 longitudinally against the influence of the springs 21 and 22. This movement of the rods 16 and 17 will cause the plates to cut the material 90 from the spade elements and render the discharge of such material easy.

What is claimed is:—

A post hole digger comprising a handle, 95 opposed transversely curved spade elements secured to one end of said handle and having their upper ends extending substantially transverse the handle, rods slidably mounted on the handle and movable through the upper ends of respective spade elements, stripping plates carried by said rods re- 100

spectively with their upper ends extending in the same general direction as the upper ends of the spade elements and their lower ends extending substantially longitudinally of the handle and engaging the inner faces of respective spade elements, and spring means constantly tending to hold said rods in position to dispose the stripping plates at

substantially the upper end of respective spade elements.

In testimony whereof, I affix my signature, in the presence of two witnesses.

JAMES M. DAY.
